UNITED STATES PATENT OFFICE

GEORGE A. HULL, OF CHICAGO, ILLINOIS, ASSIGNOR TO EQUIPMENT SPECIALTIES COMPANY, OF CHICAGO, ILLINOIS, A CORPORATION OF ILLINOIS

REFRIGERATOR CAR

Application filed February 4, 1929. Serial No. 337,291.

The present invention relates to refrigerator cars, and is more particularly concerned with floors for refrigerator cars and the like. It has been customary in refrigerator cars to 5 provide a false bottom, which encloses a plurality of layers of heat insulating material, such as asbestos paper, fiber, fabric or the like, and a layer of plastic waterproof compound above the insulating material and below the floor, primarily for the purpose of preventing water from seeping through the floor into the insulation.

In the refrigerator cars of the prior art, it has been necessary, however, to pierce this 15 waterproof layer at a plurality of points with nails for the purpose of securing the car flooring in place above the compound, and the presence of nails, bolts and other fastening means passing through the waterproofing 20 defeats the purpose of the waterproofing and permits the water to seep through into the fibrous insulation.

This matter is of particular importance in the shipment of lettuce and other products 25 where it has become the practice to pile ice in the main portion of the car among the boxes in order to keep the product in the best condition, and this practice is ordinarily termed "body icing".

30 The water resulting from the melting of the ice placed in the main part of the car seeps through the flooring and points of perforation of the waterproof layer, and as a result the insulation soon becomes water-logged and practically useless as a heat insulator, since its insulating quality depends 35 in a large measure upon the presence of the dead air spaces between the insulating fibers.

When the insulation is in this condition it 40 may also become frozen, and the alternate thawing and freezing of the waterlogged insulation and the timbers causes great deterioration of the floor structure, and the maintenance of the floor has been very expensive 45 in the cars of the prior art. The stringers and adjacent parts tend to split and rot, and when the wood and insulation has once become wet it remains so due to the fact that it is so enclosed as to prevent evaporation due 50 to ventilation.

One of the objects of the present invention is the provision of an improved refrigerator car floor construction, in which the foregoing and other difficulties have been overcome by the provision of an imperforate 55 waterproof layer below the flooring of the car.

Another object is the provision of a floor construction which is provided with ventilation conduits for facilitating the drying out 60 of the floor after it has been wet by body icing or otherwise.

Another object of the invention is the provision of a novel method of securing the flooring 65 in refrigerator cars with a minimum of labor and without producing perforations in the waterproofing layer below the flooring.

Another object is the provision of a novel threshold and flooring structure for refrigerator cars whereby the flooring may be firmly 70 secured at the doors without nailing through the waterproofing and whereby the car is adapted to drain over the sills without seeping into the insulation.

Another object is the provision of a novel 75 bulkhead supporting structure which permits the ventilation beneath the flooring and which requires no bolts passing through the waterproofing layer of the floor.

Another object of the invention is the provision of a refrigerator car structure having 80 a novel method of ventilation for the purpose of drying out the flooring when the car is running without ice and under ventilation.

Another object is the provision of a novel 85 insulated floor construction which may be more economically constructed due to the elimination of one or more layers of false flooring required in the structures of the prior art.

Other objects and advantages will be apparent from the following description and from the accompanying drawings in which similar characters of reference indicate similar parts throughout the several views.

Referring to the drawings, of which there are five sheets,

Fig. 1 is a longitudinal section through a refrigerator car constructed according to the

present invention, showing the complete ventilating system;

Fig. 2 is a transverse section of the flooring showing the construction of the floor at the 5 threshold and side wall;

Fig. 3 is a similar section taken just inside the ice compartment looking toward the main compartment with the bulkhead removed;

Fig. 4 is a plan view of a portion of the 10 flooring adjacent the threshold;

Fig. 5 is a detail sectional view through the flooring at the threshold;

Fig. 6 is a detail sectional view of the floor 15 construction adjacent a side wall;

Fig. 7 is a section view through the floor construction taken longitudinally of the car at the post bearing rail;

Fig. 8 is a view similar to Fig. 4, showing a modified form of threshold construction;

Fig. 9 is a view similar to Fig. 4, showing a modified construction;

Fig. 10 is a view similar to Fig. 5 of the same modified construction.

Referring to Fig. 1, 10 indicates the refrigerator car in its entirety, but as the invention relates particularly to the floor construction, the embodiment shown is to be regarded as merely exemplary of one of the possible forms which the invention may take. The 25 exact details of the rest of the refrigerator car may vary considerably within the scope of the present invention, and many of the details illustrated may be eliminated entirely while still utilizing the important features 30 of the invention as set forth in the appended claims. With regard to the ventilating system of the car for drying out the flooring when the car is running without ice under 35 ventilation, the car should be provided with ventilation openings 11 and 12 adjacent each end of the car and communicating through the chambers 13 and 14 with a ventilation 40 conduit 15 beneath the flooring 16. In the modern refrigerator car construction which 45 is adapted both for body icing and for use with ice piled in ice chambers, the ventilation openings 11 and 12 may consist of hatchways leading to the ice chambers 13 and 14 respectively, and located at the ends of the 50 car, but other forms of ventilation openings may be employed as well with the ventilation conduit underneath the flooring.

When it is desired to dry out the flooring, 55 the closures 17 and 18 of the hatchways 11 and 12 may be propped open as shown in the dotted line positions in such manner that the travel of the car will cause the air to flow down one hatchway and up out of the other, and at least a portion of the air will pass 60 through the conduit 15 beneath the flooring, drying out the flooring 16 on its underside and tending to keep the boards in good condition. The direction of the air currents when the car is travelling to the left in Fig. 1 is 65 indicated by the curved arrows.

Since the present invention relates particularly to floor construction, and since the walls and ceiling of the car may take any conventional form, the walls and ceiling have been diagrammatically illustrated, and it is sufficient to say that it includes the usual side walls 19 and 20, end walls 21 and 22 and ceiling 23, and the car is customarily provided with door openings 24 located adjacent the middle of the car on each side and having insulated doors 25 and 26, all exterior parts of the car being provided with the usual heat insulation. The car is provided adjacent each end with a bulkhead 27, 28 preferably comprising a plurality of sheet metal sections 70 having channels 29 at their edges forming columns for the support of the bulkhead and for the support of a wooden wall 30. The sheet metal sections 29 are provided with the usual ventilating openings 31 adjacent the top of the ice chambers 13 and 14 and communicating with the main compartment 32 and with the ventilation openings 33 below the ice chamber between the columns 29.

The ice chambers 13 and 14 formed by 75 bulkheads 27 and 28 are provided with waterproof drainage pans 34 located beneath the ice grating 35, and substantially lower than the lowest portion of the waterproof layer 36 beneath the flooring 16. The drainage 80 pans 34 are provided with well traps 37 which permit the water to drain out of the pans, but prevent the air from entering.

Referring to Figs. 2 and 6, the construction of the car floor is here illustrated in detail. The supporting structure for the floor includes the usual side sills 38 extending longitudinally of the car, and a plurality of intermediate sills 39, which may support a false flooring 40 for the purpose of forming a plurality of dead air spaces 41. The side sills 38 may be provided with a Z-bar 42, having one flange 43 disposed beneath the sills 38, and the opposite flange 44 adapted to support the false flooring 40.

Above the false flooring 40 the car may be provided with a plurality of stringers 45 of sufficient thickness to lie flush with the tops of the sills 38 and located above the Z-bars 42 and sills 39 respectively. If desired, the dead air space 41 may be filled with heat insulating material, such as asbestos paper, fabric, etc., secured to the stringers 45 in the usual manner, but the preferable construction consists in covering the stringers 45 with a layer 46 of relatively stiff heat insulating material or board form insulation, such as that which is manufactured from the bagasse of sugar cane, and which may be purchased on the open market. The board form insulation may be any stiff heat insulating material having a high heat insulating value and having sufficient compressive strength to support a portion of the weight of the load 110 transmitted from the flooring 16.

If desired, the layer 46 of heat insulating material may consist of a plurality of sheets of board form insulation laid one above the other as shown in Fig. 10 of the drawings, thereby eliminating the heat insulating material, such as asbestos paper, fabric, etc., which is usually placed in the dead air space 41. This modified construction will be described in detail hereinafter.

Above the heat insulating layer 46 the car floor is provided with a layer of waterproof material, which may consist of initially plastic asphaltum compound poured on hot on top of the board form insulation, and forming a solid and waterproof layer adapted to protect the insulating material from the water seepage. The waterproof layer 47 may also include laminations of paper, fabric, and/or felt, impregnated and cemented together with hot asphaltum set in place upon the board form insulation.

In the embodiment shown in Fig. 6, the waterproofing layer indicated in its entirety at 47, includes a lower layer 48 of roofing felt, and an upper layer 49 of asphaltum or other pliable waterproof material covering and impregnating the roofing felt, and the two layers described are continued upward at the side and end walls of the car, forming an upwardly extending waterproof layer 50 in each of the outside walls. The waterproof layer described hardens on cooling into a solid body of sufficient compressive strength to support a portion of the load, but it also has sufficient flexibility to prevent cracking at the lower extremes of temperature.

Other forms of waterproof layers which may be employed are layers of copper, zinc, galvanized iron, or other metal formed as illustrated in the drawings and extending upward on the sides of the car to form a metal pan beneath the flooring.

The flooring 16 is located above the waterproof layer 47, and is maintained in spaced relation to the waterproof layer by means of a plurality of spacing members 51, which may consist of relatively thin strips of wood extending in the same direction as the stringers 45 and preferably located above the stringers 45 to be most effectively supported thereby.

The flooring 16 may consist of a plurality of boards of any form, but tongue and groove flooring is preferably employed in order to provide a relatively strong construction in which the separate boards are firmly connected to each other and to the car. If desired, the flooring 16 may be provided with a plurality of small holes for facilitating drainage, the holes being bored at random after the car has been constructed, and at the points where the water may gather on the top of the flooring.

One of the most important features of the present invention consists in the securing of

the flooring 16 as well as the spacers 51 without the use of nails, screws or bolts driven through the waterproof layer 47 into the stringers 45 as has been the custom in the refrigerator cars of the prior art. No nails are driven through the flooring or spacer strips, but the flooring is secured at its ends adjacent the walls and threshold of the car and the spacer strips 51 may be maintained in position by the pressure of the flooring, confining the strips between the waterproof layer and the flooring.

In order to secure the flooring together in sections so that the sections may be removed as a unit, the flooring may be provided with channeled metal members 100 having a web 101 and side flanges 102 and the channeled members 100 may be secured to the flooring by a plurality of bolts 103. The web 101 of the channeled members 100 is of sufficient width so that the spacers 51 may be received between the side flanges 102, and the side flanges 102 are thereby adapted to definitely position the spacers 51 above the stringers. The ends of the channeled members 100 are preferably beveled as at 104 so that they project beyond the edge of the last board in a section and as each end is beveled at the same angle, the ends of the channeled members will fit against each other and extend beneath the boards of the adjacent sections, thereby aligning the different sections of flooring as shown in Fig. 4.

If desired, the flooring may be secured together in sections by means of the spacers 51, or in some embodiments of the invention the separate boards may be secured solely at their ends, and the spacers 51 may be held in proper position by the pressure of the flooring and by adhesion of the spacers to the waterproof layer beneath the flooring.

The flooring 16 may be secured at its ends adjacent the side walls by a securing member 52 adapted to engage the top of the flooring at the end, and also preferably engaging the ends of the flooring to prevent injury to the waterproofing 50. The securing member 52 may consist of a wooden rail which is rabbed as at 53 and provided with a downwardly extending portion or flange 54 adapted to be received between the ends of the flooring 16 and the waterproofing 50.

The rail 52 extends from the door post to the end of the car and after the flooring has been put in place and the crevices 55 and 56 have been filled with asphaltum, the rail 52 may be wedged in between the wall studs 57 and the ends of the flooring 16, clamping the flooring firmly in place and clamping the waterproofing 50 to the studs 57. The rail 52 is secured to the studs by a plurality of bolts 58 and it may also be rabbed at 59 and 60 to receive a plurality of wall boards 61 and 62, forming the dead air spaces in the wall.

If waterproofing fabric is used, it is preferably bent upward at 63 forming a curve with a considerable radius to prevent cracking and the space on both sides of the curved portion 63 at 55 and 56 is filled in with asphaltum.

- It will thus be observed that the flooring 16 may be secured at its ends without the use of any nails or other securing devices perforating the waterproof layer, and furthermore, the floor may be put in place with a minimum of expenditure of time and labor. The waterproof layer not only extends underneath the flooring, but upward on the walls of the car to a point past the probable water line and the corners of the waterproofing are given additional protection in the form of a filling of asphaltum in the vacant spaces at the ends of the boards.
- 20 The upper surface of the stringers 45 may be sloped slightly from the middle of the car toward the ends to facilitate drainage, if desired, and the air ventilation conduit 15 is adapted to permit the drying out of the lower side of the flooring when the car is travelling under ventilation.

At the door openings 24, it is not desirable to employ the securing rails 52 for securing the flooring 16 in place, but the flooring may be secured at its ends by the threshold plates shown in Figs. 2, 4 and 5, in a similar manner without obstructing the doorway. The waterproofing layer 47 may be bent upward adjacent the door posts 64 and extended outward over the sill 38 at the doorway, and bent downward as at 65 outside of the sill. The cracks about the door posts 64 are preferably filled with asphaltum, and the threshold is provided with a wooden filler strip 66 beneath the threshold at the ends of the flooring 16.

The threshold plate 67 comprises a sheet metal member having a downwardly extending flange or apron 68 adapted to form a facing for the car wall beneath the door opening 24, protecting the sill 38 and clamping the waterproof layer against the sill by means of the bolts 69, which also secure the Z-bars 42. The threshold plate 67 is also provided with a flange 70 extending inward from the apron 68 and upward at a slight angle to form a tapered door opening which may be sealed by means of the usual doors having inwardly tapered edges.

55 At the point 71 adjacent the ends of the flooring 16, the threshold plate 67 is bent upward to cover the ends of the flooring, and at 72 it is bent inward at right angles to form an attaching flange 73, and the attaching flange is preferably secured flush with the upper edge of the flooring 16 by a plurality of relatively short screws 74.

The threshold plate 67 is extended beyond the door post 64 at each side of the door as 65 at 75, in order to secure the flooring imme-

dately opposite the door post 64, and the threshold plate may be provided with upwardly extending flanges 105 adapted to be bolted to the door post 64. The waterproofing layer 47 is extended upward between the flanges 105 and the door post 64 and clamped between the flange and the door post at 106. The upwardly extending portion of the waterproof layer 50 is clamped between the door post and the rail 52, and in effect a complete waterproof pan or receptacle is provided extending upward on the walls of the car at all points except at the threshold where the pan drains out over the sill.

Referring to Fig. 8, a modified form of threshold plate is illustrated in this figure, in which the threshold plate is adapted to extend longitudinally into a slot 76 in the ends of the flooring adjacent the door. The flooring may then be protected by a separate metal strip 77 secured by screws 78.

Referring to Figs. 1, 3 and 7, another feature of the present invention is the floor construction beneath the bulkhead 27, by means of which all bolts or other fastening means passing through the waterproof layer are eliminated. For this purpose, the car may be provided with a post bearing rail 79 comprising an elongated sheet metal member having a downwardly extending flange 80 adapted to overhang the drainage pan 34 and adapted to reinforce the post bearing rail.

The post bearing rail is provided at each end with upwardly turned attaching flanges 82, which may be secured to the studs or side walls by a plurality of bolts 81, and the bolts 81 may likewise secure the floor securing rail 52 in place.

The body portion 83 of the post bearing rail preferably slopes downward toward the drainage pan 34 for the purpose of facilitating the drainage of any water which may be above the flooring 16, and the last board 84 of the flooring may be tapered to permit the slope of the bearing rail. The body portion 83 of the post bearing rail provides a support to which the column 29 of the metal bulkhead sections may be secured by means of the usual flanged feet, and it is unnecessary to extend any bolts through the wooden post bearing rail 85, thereby maintaining the waterproof layer 47 imperforate at all points.

The waterproof layer 47 is preferably curved downward over an arc of considerable radius at 86 overlapping the upwardly extending flange 87 of the drainage pan 34 at 88, and the downwardly extending flange 80 of the post bearing rail clamps the waterproofing in place against the side of the drainage pan 34. The crevices 89 adjacent the curved portion 86 of the waterproofing layer are filled with asphaltum, and the asphaltum layer may be extended through the apertures 90 which are provided in the flange 130

80 to connect the air conduits 15 with the drainage pan 34.

Referring to Figs. 9 and 10, a modified form is illustrated in these figures, from, 5 which the usual fabric insulation of the floor has been entirely eliminated. The board form insulation 46 in this embodiment comprises a plurality of layers of the material illustrated in the previous figures, laid over 10 the stringers to cover the entire floor area.

The separate layers of board form insulation are laid with broken joints wherever joints are necessary and nailed directly to the 15 stringers forming an insulating layer which may be approximately two inches thick. The thickness of the layer will vary with the heat insulating value of the board form insulation selected, but the layer should be of sufficient thickness to provide substantially 20 equivalent or better heat insulation than that employed in the present construction where heat insulating fabric is used in the dead air spaces. The other details of construction 25 may be substantially the same as previously described.

The operation of the refrigerator car in the drying out or ventilation of the flooring has been already described. It will be evident that since the entire floor area is covered with an imperforate layer of waterproofing material overhanging the drainage pans and overhanging the threshold and extending upward on the side walls, it is practically impossible for any water to seep 30 through the waterproof material into the heat insulation and the heat insulating quality of the insulation is maintained at all times. Furthermore, the stringers and adjacent parts are not subjected to waterlogging or rotting as in the floor constructions 35 of the prior art, and the flooring itself is maintained in good condition by drying out the flooring whenever the car is running without ice under ventilation. The use of asphaltum 40 applied directly to one side of the board type insulation provides a waterproofed insulation which is maintained in good condition even though water may penetrate to the edges 45 of the insulation and the use of this composite material eliminates a large amount of 50 labor involved in installing the fabric type insulation between the stringers, thereby greatly reducing the cost of construction.

While I have illustrated a preferred embodiment of my invention, many modifications may be made without departing from the spirit of the invention, and I do not wish to be limited to the precise details of construction set forth, but desire to avail myself 60 of all changes within the scope of the appended claims.

Having thus described my invention, what I claim is new and desire to secure by Letters Patent of the United States, is:

65 1. In a refrigerator car floor construction,

the combination of sills with a layer of heat insulating material carried by said sills, an imperforate layer of waterproofing material carried by said heat insulating material, a layer of flooring above said waterproofing 70 and spacers between said flooring and waterproofing for forming a ventilation conduit between said waterproofing material and flooring, said flooring extending to a point adjacent the oppositely located ice chambers in said refrigerator car and said conduits being open at each end, whereby a circulation 75 of air is permitted from said ice chambers through said conduit.

2. In a refrigerator car floor construction, 80 the combination of sills with a layer of stiff heat insulating material carried by said sills, a layer of waterproofing material carried by said heat insulating material and extending over a threshold, flooring supported above 85 said waterproofing layer and a threshold plate adapted to engage said flooring adjacent said threshold to secure said flooring in place.

3. In a refrigerator car floor construction, 90 the combination of sills with a layer of stiff heat insulating material carried by said sills, a layer of waterproofing material carried by said heat insulating material and extending 95 over a threshold, flooring supported above said waterproofing layer and a threshold plate adapted to engage said flooring adjacent said threshold to secure said flooring in place, and spacers between said flooring and waterproofing and located above said sills to support said flooring and form a ventilation 100 conduit.

4. In a refrigerator car floor construction, 105 the combination of sills with a layer of stiff heat insulating material carried by said sills, a layer of waterproofing material above said heat insulating layer and extending upward at a car wall, a layer of flooring and a floor securing member engaging above said flooring 110 and secured to said wall.

5. In a refrigerator car floor construction, 115 the combination of sills with a layer of stiff heat insulating material carried by said sills, a layer of waterproofing material above said heat insulating layer and extending upward at a car wall, a layer of flooring and a floor securing member engaging above said flooring and secured to said wall, said floor securing member also being adapted to engage the 120 ends of said flooring.

6. In a refrigerator car, the combination 125 of a floor supporting structure and walls with a waterproof layer on said structure and extending upward on said walls, flooring on said waterproof layer, and a flooring securing member carried by said walls and confining said flooring in place on said waterproofing layer.

7. In a refrigerator car, the combination 130 of a floor supporting structure and walls

- with bulkheads forming ice chambers, an imperforate waterproof layer on said structure and extending upward on said walls, flooring on said waterproof layer and extending to 5 points adjacent said bulkheads, a flooring securing member carried by said walls and confining said flooring in place on said waterproofing layer, and spacers between said flooring and said waterproof layer to form a 10 ventilation conduit extending from one bulkhead to the other, said conduit being open at both ends to permit circulation of air from said ice chambers.
8. In a refrigerator car, the combination 15 of a floor supporting structure and walls with a layer of waterproofing material over said supporting structure, an ice chamber having a drainage pan in said car, a bulkhead between said ice chamber and the balance of said car, 20 a post bearing rail having support at the walls of said car, said bulkhead being carried in part by said post bearing rail, a layer of flooring interposed between said post bearing rail and said waterproofing, and spacers beneath 25 said flooring forming a ventilation conduit.
9. In a refrigerator car, the combination of a floor supporting structure and walls with a layer of waterproofing material over said supporting structure, an ice chamber having a 30 drainage pan in said car, a bulkhead between said ice chamber and the balance of said car, a post bearing rail having support at the walls of said car, said bulkhead being carried in part by said post bearing rail, a layer 35 of flooring interposed between said post bearing rail and said waterproofing, spacers beneath said flooring forming a ventilation conduit, and a flange carried by said post bearing rail overhanging said drainage pan, 40 said flange having openings to said ventilation conduit.
10. A refrigerator car floor construction comprising the combination of a plurality of 45 sills, with a covering of integral board form heat insulation extending from one side of the car to the other side carried by said sills and secured thereto forming a supporting surface and forming the major heat insulation for said floor, and an imperforate layer of 50 waterproofing material carried by and extending over said board form insulation and protecting said insulation from water.
11. A refrigerator car floor construction comprising the combination of a plurality of 55 sills, with a covering of board form heat insulation carried by and extending over said sills and secured thereto forming a supporting surface and forming the major heat insulation for said floor, and an imperforate layer of 60 waterproofing material carried by said board form insulation and protecting said insulation from water, said covering comprising a plurality of layers of stiff insulating material secured to the upper surface 65 of said sills.

12. A refrigerator car floor construction comprising the combination of a plurality of sills, with a covering of board form heat insulation carried by and extending over said sills and secured thereto forming a supporting surface and forming the major heat insulation for said floor, an imperforate layer of 70 waterproofing material carried by said board form insulation and protecting said insulation from water, and a layer of flooring supported in spaced relation to said waterproofing material to form a ventilation conduit open at both ends between said flooring and waterproofing material. 75
13. A refrigerator car floor construction comprising the combination of a plurality of sills, with a covering of board form heat insulation carried by said sills and secured thereto forming a supporting surface and forming the major heat insulation for said floor, an imperforate layer of 80 waterproofing material carried by said board form insulation and protecting said insulation from water, and a drain pan forming the bottom of an ice chamber, said waterproofing material extending continuously over said board form insulation into said drain pan. 85
14. A refrigerator car floor construction comprising the combination of a plurality of sills, with a covering of board form heat insulation carried by said sills and secured thereto forming a supporting surface and forming the major heat insulation for said floor, an imperforate layer of 90 waterproofing material carried by said board form insulation and protecting said insulation from water, a drain pan forming the bottom of an ice chamber, said waterproofing material extending continuously over said board form insulation into said drain pan, and a layer of 95 flooring supported in spaced relation to said waterproofing material to form a ventilation conduit open at both ends between said flooring and waterproofing material. 100
15. A refrigerator car floor construction comprising the combination of a plurality of sills, with a covering of board form heat insulation carried by said sills and secured thereto forming a supporting surface and forming the major heat insulation for said floor, a layer of 105 waterproofing material carried by said board form insulation and protecting said insulation from water, a drain pan forming the bottom of an ice chamber, said waterproofing material extending continuously over said board form insulation into said drain pan, and a layer of 110 flooring supported in spaced relation to said waterproofing material to form a ventilation conduit open at both ends between said flooring and waterproofing material. 115
16. A refrigerator car floor construction comprising the combination of a plurality of sills, with a covering of board form heat insulation carried by said sills and secured thereto forming a supporting surface and forming the major heat insulation for said floor, a layer of 120 waterproofing material carried by said board form insulation and protecting said insulation from water, a drain pan forming the bottom of an ice chamber, said waterproofing material extending continuously over said board form insulation into said drain pan, a layer of flooring supported in spaced relation to said waterproofing material to form a ventilation conduit between said flooring and waterproofing material, and a post bearing rail having a bearing flange resting on said flooring, and having upwardly extending bearing flanges secured to the car walls. 125

17. A refrigerator car floor construction 130

comprising the combination of a plurality of sills, with a covering of board form heat insulation carried by said sills and secured thereto forming a supporting surface and forming the major heat insulation for said floor, a layer of waterproofing material carried by said board form insulation and protecting said insulation from water, a drain pan forming the bottom of an ice chamber, said waterproofing material extending continuously over said board form insulation into said drain pan, a layer of flooring supported in spaced relation to said waterproofing material to form a ventilation conduit between said flooring and waterproofing material, and a rail having a downwardly extending flange overlying the edge of said drain pan and waterproofing material and formed with apertures leading to said ventilation conduit.

17. A refrigerator car floor construction comprising the combination of a plurality of sills, with a covering of board form heat insulation carried by said sills and secured thereto forming a supporting surface and forming the major heat insulation for said floor, a layer of waterproofing material carried by said board form insulation and protecting said insulation from water, said layer of waterproofing material extending upward on the walls of the car, and a common clamping member for clamping the waterproof material to said wall and for clamping said flooring down on said waterproof material.

18. A refrigerator car floor construction comprising the combination of a plurality of sills, with a covering of board form heat insulation carried by said sills and secured thereto forming a supporting surface and forming the major heat insulation for said floor, a layer of waterproofing material carried by said board form insulation and protecting said insulation from water, said layer of waterproofing material extending upward on the walls of the car, and a common clamping member for clamping the waterproof material to said wall and for clamping said flooring down on said waterproof material, said clamping member being formed with a shoulder for engaging the ends of said flooring to prevent longitudinal sliding of said flooring.

19. In a refrigerator car, the combination of an enclosure, including walls and roof and having ventilation openings at each end of said car, with a bulkhead located adjacent one end of said car and forming a refrigeration chamber at said end, said refrigeration chamber having a water pan at its bottom, said car having a cargo chamber located on the other side of said bulkhead, a floor structure including supporting members, an imperforate waterproof layer carried by said supporting members, heat insulation for said floor structure arranged below said water-

proof layer and protected thereby, and a car flooring supported in spaced relation to and above said waterproof layer, said car flooring extending to a point adjacent said bulkhead forming a conduit open at each end between said flooring and waterproof layer for drying out said flooring by ventilation through the openings at each end of said car when the car is traveling under ventilation.

20. In a refrigerator car the combination of an enclosure, including walls and roof and having ventilation openings at each end of said car, with a bulkhead located adjacent one end of said car and forming a refrigeration chamber at said end, said refrigeration chamber having a water pan at its bottom, said car having a cargo chamber located on the other side of said bulkhead, a floor structure including supporting members, an imperforate waterproof layer carried by said supporting members, heat insulation for said floor structure arranged below said waterproof layer and protected thereby, and a car flooring supported in spaced relation to and above said waterproof layer, said car flooring extending to a point adjacent said bulkhead and forming a conduit open at each end between said flooring and waterproof layer for drying out said flooring by ventilation through the openings at each end of said car when the car is traveling under ventilation, said imperforate waterproof layer being arranged to drain toward said water pan and overlapping said water pan at said bulkhead.

21. In a refrigerator car a floor structure comprising a plurality of supporting sills with a layer of stiff board form insulation formed of fibers of bagasse, carried by said sills and forming the major heat insulation for said floor structure, an imperforate layer of waterproof material carried by the upper surface of said board form insulation and secured thereto, and a layer of standard flooring carried above said imperforate waterproof layer and supported in spaced relation thereto to form a conduit open at both ends.

In witness whereof I hereunto subscribe my name this 31st day of Jan., 1929.

GEORGE A. HULL.
